CLAIM

I claim the ornamental design for a wellness product dispensing container, as shown and described.

DESCRIPTION

FIG. 1 shows a perspective view of a wellness product dispensing container of the present invention;

FIG. 2 shows a front view of the wellness product dispensing container of FIG. 1;

FIG. 3 shows a back view of the wellness product dispensing container of FIG. 1;

FIG. 4 shows a right side view of the wellness product dispensing container of FIG. 1

FIG. 5 shows a left view of the wellness product dispensing container of FIG. 1;

FIG. 6 shows a top view of the wellness product dispensing container of FIG. 1; and,

FIG. 7 shows a bottom view of the wellness product dispensing container of FIG. 1.
